UNITED STATES PATENT OFFICE.

FLEMING McCONNELL, OF FLORENCE, PENNSYLVANIA, ASSIGNOR OF ONE-HALF TO DANIEL M. McCONNELL, OF SAME PLACE.

HOG-NOSE RINGER.

SPECIFICATION forming part of Letters Patent No. 275,241, dated April 3, 1883.

Application filed January 15, 1883. (No model.)

To all whom it may concern:

Be it known that I, FLEMING McCONNELL, of Florence, in the county of Washington and State of Pennsylvania, have invented certain new and useful Improvements in Hog-Nose Ringers; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved hog-nose ringer, and Fig. 2 is a longitudinal vertical section of the same.

Similar letters of reference indicate corresponding parts in both the figures.

My invention has relation to devices for inserting nose-rings in the snouts of hogs; and it consists in the improved construction and combination of parts of a device having a snapping jaw operated by a trigger, as hereinafter more fully described and claimed.

In the accompanying drawings, the letter A indicates the handle and casing of the device, which is shaped somewhat similar to the stock or handle of a pistol. The outer end of the casing is provided with a projection, B, forming a rigid jaw, while the movable snapping jaw C projects from the central part, D, of the hammer E. The hammer is actuated by a spring, F, which is fastened in the stock or handle, and operates upon a projection, G, upon the lower edge of the hammer. The hammer is pivoted upon a bolt or screw, H, in the front part of the casing, and is cocked by a projection, I, upon its upper edge. A rear-

wardly-extending projection, J, bears against the trigger K, which is pivoted at its upper end in the frame, and is engaged by a projection, L, upon the front edge of the trigger, when cocked, the latter being drawn forward by a spring, M. When the trigger is drawn back it releases the hammer, which is snapped by the spring, and the ring, which is placed between the two jaws and placed to the nose of the hog, will be inserted in a moment of time. In this manner hogs may be ringed while eating or sleeping, there being no necessity for handling or holding the hog, as the operation is performed in a moment.

The spring actuating the hammer may be either, as shown in the drawings, of a spiral shape and drawing the projection, or it may be flat and bear against it, without affecting my invention.

Having thus described my invention, I claim and desire to secure by Letters Patent of the United States—

In a hog-nose ringer, the combination of the casing and handle A, having rigid jaw B, the hammer E, having jaw C, upper projection, I, lower projection, G, and rear projection, J, and pivoted upon bolt H, spring F, and trigger K, having projection L and spring M, as and for the purpose shown and set forth.

In testimony that I claim the foregoing as my own I have hereunto affixed my signature in presence of two witnesses.

FLEMING McCONNELL.
